UNITED STATES PATENT OFFICE.

LEE S. CHADWICK, OF EAST CLEVELAND, OHIO, ASSIGNOR TO THE CLEVELAND FOUNDRY COMPANY, OF CLEVELAND, OHIO, A CORPORATION OF OHIO.

HEAT-DISTRIBUTER.

1,150,172.

Specification of Letters Patent. Patented Aug. 17, 1915.

Application filed April 17, 1914. Serial No. 832,437.

To all whom it may concern:

Be it known that I, LEE S. CHADWICK, a citizen of the United States, residing at East Cleveland, in the county of Cuyahoga and State of Ohio, have invented a certain new and useful Improvement in Heat-Distributers, of which the following is a full, clear, and exact description, reference being had to the accompanying drawings.

10 This invention relates to heat distributers for use particularly in ovens of the type shown in my copending application No. 797,217, for stoves, filed October 25, 1913.

The heat is supplied to the oven shown 15 in the aforesaid application, by a burner that is located beneath the oven and which discharges its products of combustion into the oven through an opening in the bottom wall thereof. The opening is considerably 20 smaller than the area of said wall, and, in the particular embodiment shown in said application, is located to one side and forward of the center of the oven. It will be readily seen that, from this arrangement, 25 unless some suitable heat deflector or distributer is provided, the temperature of that portion of the oven above the burner will be much higher than the temperature of the surrounding portions, and such a condition 30 would have a disastrous effect, in cooking, as can well be understood. Another difficulty experienced, in the absence of a properly constructed deflector or distributer, is the creating of a downward draft in the 35 chimney of the burner by the closing of the oven door, which results in the flame being blown out, or a disagreeable smoking of the burner.

The objects of this invention are to provide 40 a heat distributer that may be placed in an oven of the above mentioned type, which will distribute the heat evenly throughout the entire lower portion of the oven, as it rises through the opening in the 45 bottom wall, in order that the temperature of the oven will be uniform throughout the entire space above the plane of said distributer; and to so construct and form the distributer that it will act to deflect the 50 draft, incident to the closing of the oven door, from the direction of the burner and prevent it from having any effect thereon. As a more limited object, my invention provides 55 a deflector of the aforesaid nature which is composed of a pair of sheet metal

plates, one of which is superimposed above the other and both of which are carried by a grid that forms the bottom shelf of the oven; to make the lower of the plates the larger, so that it will project beyond the 60 edges of the upper plate, and to so form it and locate it with respect to the other plate and the burner, that the desired distribution of heat is accomplished, as will be clearly brought out hereinafter.

Further objects, which are attained through the novel construction of my heat distributer, will become apparent as this description proceeds.

In the drawings, Figure 1 represents a 70 transverse, vertical section through the lower portion of an oven having one of my distributers therein, the view including a part of the supporting structure and a portion of the burner chimney, and being taken on the line 1—1 of Fig. 2; Fig. 2 is a section on the line 2—2 of Fig. 1, and looking in the direction of the arrows; Fig. 3 is a perspective view of the distributer and the grid whereby it is carried; and Fig. 4 is a perspective of the near corner of the distributer (as it is shown in Fig. 3) and includes a part of the bottom plate of the oven.

Since the oven construction forms no part of my present invention, it will be described 85 only in a general way as comprising the front wall 1, rear wall 2, side walls 3 and 4, and bottom wall 5. The bottom wall 5 is provided with an opening 6 that is located to one side and forward of the center of said 90 wall, and through which the products of combustion rise from the chimney 7 of the burner to the interior of the oven. The bottom plate 8 is spaced from the bottom wall 5 and has an opening 9 which is located above 95 the opening 6, and its side edges are turned upward and inward to form ledges 10 and 11, as shown clearly in Fig. 1.

The oven shown herein is of the class that can be used either as one operating under 100 the usual principle of circulating the heat through the oven, or as one commonly known as the "fireless" type. Therefore, the walls of the oven are filled with a heat insulating material, and a lagged damper plate 12 occupies the space between the bottom plate 8 and the bottom wall 5 of the oven and is adapted to be slid forward, by the rod 13, to cover the opening 6, when it is desired to use the oven as a "fireless" cooker.

110

The grid which forms the bottom shelf of the oven and which carries my heat distributer, is supported by the ledges 10 and 11. It consists of a rectangular wire frame, 5 the front and rear members of which are represented by 14 and 15, respectively, and the ends of these members are connected by the side members 16 and 17, which rest directly upon the ledges 10 and 11, respectively. 10 A series of U-shaped members 18 form the supporting surface of the grid, and the ends of the parallel branches of the U-shaped members 18 rest upon the front and rear members 14 and 15 of the frame and are 15 secured thereto, by any suitable method, as by welding. Secured to the underneath surfaces of the members 18 and extending transversely thereof from the side member 17 of the grid to within a short distance of 20 the other side member, are a pair of rods 19 and 20, the first being located a little forward of the transverse center of the grid while the latter is situated about midway between the former rod and the rear member 25 15 of the grid frame.

The distributer is preferably constructed from a single piece of sheet metal that is formed in such a manner as to comprise three distinct sections or portions, such sections being referred to hereinafter, respectively, as an upper plate 21, a lower plate 22, and a front plate 23 which connects the forward edges of the upper and lower plates. The rear edge of the lower plate is 30 turned downward and about the wire 19, as shown at 24, the downturned portion of the plate being notched for the accommodation of the parallel branches of the U-shaped members 18, as shown at 25 in Fig. 1. The 35 forward edge of the plate 21 is also turned downward, then rearward around the closed ends of the U-shaped members 18 and is then directed downward to form the front plate 23 of the distributer. The front plate 40 45 23 is inclined a little forward toward its lower edge, where it joins the front edge of the lower plate 22, a slight distance above the bottom plate 8 of the oven.

The lower plate 22 is inclined upward and 50 rearward from its forward edge until it very closely approaches the underneath surface of the U-shaped members 18, a little to the rear of the rod 19 which defines the rear edge of the upper plate 21. From here the 55 plate 22 is gradually inclined downward toward its rear edge where it is abruptly turned upward and forward and is curled about the rod 20, (as shown at 26) whereby it is supported. The upper side of the 60 curled-over portion 26 is notched to accommodate the U-shaped members 18, as shown at 27, particularly in Fig. 1. It will be seen from the transverse section of the distributer, shown in the same figure, that the 65 70 75 side edges of the upper plate are turned

downward and inward at 28, for the purpose of strengthening the plate, and for the same purpose, the side edges of the lower plate 22 are treated in like manner, as shown at 29. The ends of the front plate 23 of the 70 distributer are turned over as shown at 30, said turned-over portion being a continuation of the turned-over portion 29 of the lower plate 22.

From Figs. 1 and 3 it will be observed 75 that the right hand side edge of the upper plate 21 extends beyond the corresponding edge of the lower plate and overlies the side member 17 of the grid and the ledge 11 whereon said members rest; while the opposite side edge of the upper plate is spaced inward some distance from the left hand side edge of the lower plate. It will be observed, also, (see Fig. 4) that a member 31 connects the forward end of the ledge 11 with the bottom plate 8 and closes the space which would otherwise be left between the right hand end of the front plate 23, and the upturned side portion of the bottom plate 8; for, it will be understood, in order to permit 80 the grid to be lowered upon the ledges 10 and 11, the front plate must be short enough to pass the inner edge of the ledge 11. By the presence of the member 31 and the overhanging, right hand edge of the upper plate 95 21, the corner of the oven beneath the distributer is very effectively closed against the draft created by the closing of the oven door.

With the distributer constructed in accordance with the foregoing description and located within the oven as shown in the accompanying drawings, it has the effect of deflecting the heat rearwardly as it rises from the chimney of the burner. The front portion of the plate 22, which is directly above the burner, will, of course, become the 100 hottest because of the intensity of the heat at this point, and will raise the temperature of the air within the space between the plates 21 and 22, and, in that manner, transmit the heat to the upper plate 21, from the upper surface of which it radiates at a 105 temperature desirable for cooking purposes. It will be noted that a restricted passage-way is formed between the rear downturned edge of the upper plate 21 and the adjacent portion of the lower plate 22, and this acts to retard the flow of heated air between the plates, in the rearward direction, 110 causing a part of it to escape around the left hand end of the upper plate 21. It is estimated that the air which escapes from beneath the plate 21 is of about the same 115 temperature as that which rises from its surface. The rearward circulation of the heated air from the burner is somewhat retarded beneath the highest point of the lower plate 22, because of the downward inclination of the plate therebeyond. This 120 125 130 135 140

causes a slight dwell of the heated air at this point, and the directing of a portion of it toward the left hand end of the distributer. The temperature being higher at the right hand end of the plate 22, causes substantially the same degree of heat to rise from its upper surface, as escapes about the left hand end of the highest portion of said plate. When the products of combustion 10 from the burner finally pass upwardly about the left hand end and rear edge of the bottom plate 22, it is found that the temperature thereof has dropped to approximately the same degree as that of the air which rises from the upper surface of the rear portion of the plate 22, and from the upper surface of the plate 21.

From the foregoing, it will be seen, that, by the use of my heat distributer, a very uniform temperature is caused to exist throughout all parts of the oven; and, as hereinbefore pointed out, the distributer protects the burner from the draft created by the closing of the oven door. While I have described a very desirable construction for my heat distributer, and have set forth a particular location for it within the oven, I wish it to be understood that I do not confine myself to such a construction or location further than required by the terms of the annexed claims and the prior state of the art.

Having thus described my invention, what I claim is:—

1. A heat distributer comprising a substantially horizontal plate, and a second plate located therebeneath, said second plate being inclined upward toward and beyond the edge of the first mentioned plate and then downward and outward therefrom, the edge of the first mentioned plate and the adjacent portion of the second plate being spaced apart.

2. A heat distributer comprising a substantially horizontal plate having a downturned edge, and a second plate located therebeneath, said second plate being inclined upward toward and beyond the edge of the first mentioned plate and then downward and outward therefrom, the downturned edge of the first mentioned plate and the adjacent portion of the second plate being spaced apart.

3. A heat distributer comprising a substantially horizontal plate, and a second plate which is inclined upward from beneath one edge of the first mentioned plate toward and beyond its opposite edge, the second plate being turned downward and outward therebeyond, the last mentioned edge of the first plate being spaced from the adjacent portion of the second plate.

4. A heat distributer comprising a substantially horizontal plate having a downturned edge, and a second plate which is in-

clined upward from beneath the opposite edge of the first mentioned plate toward and beyond its downturned edge from where said second plate is then turned downward and outward, the downturned edge of the first mentioned plate being spaced from the adjacent portion of the second plate. 70

5. A heat distributer comprising a substantially horizontal plate, a substantially vertical plate which depends from one edge thereof, and a plate which is inclined upward from the lower edge of the vertical plate toward and beyond the opposite edge of the first mentioned plate, the inclined plate being turned downward and outward therebeyond, the edge of the first mentioned plate and the adjacent portion of the inclined plate being spaced apart. 75

6. A heat distributer comprising a substantially horizontal, rectangular plate, a second plate which is of greater width and length than the first mentioned plate located beneath said first plate, a substantially vertical plate that connects and spaces apart the corresponding edges of the first and second mentioned plates, the second plate being inclined upward from the lower edge of the vertical plate toward and beyond the opposite edge of the first mentioned plate 90 from where it is then turned downward and outward, the edge of the first plate being spaced from the adjacent portion of the second mentioned plate. 95

7. A heat distributer that is formed from a single piece of sheet metal and having a flat, substantially horizontal portion, a substantially vertical portion which depends from one edge thereof, and a portion which is inclined upward from the lower edge of the vertical portion toward and beyond the opposite edge of the first mentioned portion from where it is then turned downward and outward. 100

8. A heat distributer that is formed from a single piece of sheet metal and having a flat, substantially horizontal portion, a substantially vertical portion that depends from one edge thereof, and a portion which is inclined upward from the lower edge of the vertical portion toward and beyond the opposite edge of the first mentioned portion from where it is then turned downward and outward, the first named portion being of less breadth than the last named portion. 110

9. A device of the character described comprising, in combination, a grid that is composed of a substantially rectangular frame and a series of parallel members carried by said frame and having ends that project beyond one side of the frame, a pair of rods secured to the underneath surfaces of the parallel members and extending transversely thereof, and a single piece of sheet metal that has a portion which rests upon 125

the upper surface of the aforesaid members and has an edge which is notched, the portions between the notches being bent downward between said members and turned 5 about one of the aforesaid rods, the opposite edge of the flat portion of the plate being bent around the end of the parallel members and then downward in a substantially vertical plane from where it is then inclined 10 upward toward and beyond the edge which embraces the aforesaid transverse rod, the said plate then being turned downward and outward to a point beneath the second mentioned transverse rod where it is bent upward and about said rod, the portion of the 15 plate surrounding the last mentioned rod being notched for the accommodation of the parallel members.

10. A device of the character described 20 comprising, in combination, a grid that is composed of a substantially rectangular frame and a series of U-shaped members supported thereby, the U-shaped members having closed ends that overhang one side 25 of the frame, a pair of rods secured to the underneath surface of the U-shaped members and extending transversely thereof, and a sheet metal member that has one of its 30 ends notched and the portions between the notches turned downward between the parallel branches of the U-shaped members and about one of said rods, a portion of the sheet metal member overlying the upper surface 35 of the U-shaped members and being turned about the closed ends of said members in a manner to embrace said ends, said sheet metal member then being directed downward in a substantially vertical plane and then upward and rearward beyond its edge 40 which is turned about the aforesaid rod from where said member is inclined downward and outward to a point beneath the second of said rods, the edge of the member being bent upward and about the rod, and the portion 45 surrounding said rod being notched for the accommodation of the parallel branches of the U-shaped members.

11. A device of the character described 50 comprising, in combination, a grid that is composed of a substantially rectangular frame and a series of parallel members supported thereby, a pair of rods secured to the underneath surface of the parallel members and extending transversely thereof, and a 55 sheet metal member that has one of its ends notched and the portions between the notches turned downward between adjacent parallel members and about one of said rods, a portion of the sheet metal member overlying 60 the upper surface of the parallel members and having a part that is turned about the ends of said members in a manner to em-

brace said ends, said sheet metal member then being directed downward in a substantially vertical plane and then bent upward and rearward beyond its edge which is turned about the aforesaid rod from where the member is turned downward and outward to a point beneath the second of said rods, the edge of the member being bent upward and about the rod. 65 70 75

12. A heat distributer for ovens of the class having an opening in its bottom wall, which opening is located forward and to one side of the center of the oven, and having, also, a pair of opposed ledges which are spaced from said bottom wall, the distributer comprising, in combination, a grid that is composed of a substantially rectangular frame which is adapted to rest upon the aforesaid ledges, U-shaped members which extend from front to rear of said frame and are supported thereby, a pair of rods that are secured to the underneath surfaces of the U-shaped members and extend transversely thereof from that side of the frame adjacent the opening in the bottom wall of the oven toward the opposite side of the frame, a sheet metal member which has a notched edge, the portions between the notches being bent downward between the parallel branches of the U-shaped members and about that rod which is located nearest the front of the grid, a portion of the sheet metal member resting upon the upper surface of the U-shaped members and having an edge which extends over the ledge that is adjacent the opening in the bottom wall of the oven, the sheet metal member then being bent about the forward, closed ends of the U-shaped members and thence downward in a substantially vertical plane in proximity to the bottom wall of the oven, from where it is inclined upward toward and beyond the aforesaid notched edge of the member and in proximity to the underneath surface of the U-shaped members, the sheet metal member being then directed downward and rearward to a point beneath the other of the transverse rods, from where it is bent upward and about said rod, and a member that is of substantially the same width as one of the ledges of the oven and which extends from the forward end of one of the ledges downward to the bottom of the oven in juxtaposition to the end of the vertical portion of the sheet metal member, as and for the purpose specified. 90 95 100 105 110 115 120

In testimony whereof, I hereunto affix my signature in the presence of two witnesses.

LEE S. CHADWICK.
